[57] **CLAIM**

The ornamental design for a paint roller, as shown and described.

DESCRIPTION

FIG. 1 is a perspective view of the paint roller embodying the design of the present invention;

FIG. 2 is a front elevational view thereof;

FIG. 3 is a rear elevational view thereof;

FIG. 4 is a side elevational view thereof;

FIG. 5 is a side elevational view thereof; and,

FIG. 6 is a top plan view thereof, the bottom view being a mirror image of the top view shown in FIG. 6.

The stippling shown in FIGS. 1-6, which is partially shown for ease of illustration, represents a conventional roller material and is understood to repeat throughout the areas indicated.

FIG.1.

FIG. 2.

FIG. 3.

FIG. 4.

FIG. 5.
